(57) **ABSTRACT**

A manually actuated strapping unit for wrapping a tightening strap around a packaged item (58), includes a base plate (1) which is provided with a supporting surface (1b) for arranging on the packaged item (58). The unit further has a sealing device with which two strap layers (60), (61) can be connected permanently to each other, and is provided with a tensioning device with which a strap tension can be applied to the tightening strap. The tensioning device has a manually actuated tensioning lever (39) with which a tensioning wheel (38), arranged on a tensioning shaft (43), can be actuated. The unit further is provided with a separating device with which the strap can be severed wherein the unit includes an axial coupling (44) in a force flux from the tensioning lever (39) to the tensioning wheel (38).

**MANUALLY ACTUATED STRAPPING UNIT
FOR WRAPPING A TIGHTENING STRAP
AROUND A PACKAGE ITEM**

FIELD OF THE INVENTION

The invention relates to a manually actuated, preferably exclusively manually actuated and mobile, strapping unit.

BACKGROUND OF THE INVENTION

Strapping units of this type are frequently provided for mobile use so that a user can wrap a steel strap around a packaged item in any desired location. A generic type of these strapping units typically has a sealing device which produces a connection of two layers of the steel strap by means of multiple notchings, without using an additional sealing element, such as, for example a lead seal. For this type of strapping unit it is also typical for both the strap tension and the formation of a seal to be produced manually without the assistance of outside energy, in particular electric or hydraulic energy. For this purpose, the operator of a strapping unit according to the generic type has only to provide his own muscular power. However, the invention is also suitable for another generic type of strapping unit, in which either a sealing element, such as the already mentioned lead seal, or auxiliary energy, such as, for example, electric energy, is used for producing a welding connection in the case of plastic straps. However, a common feature of the generic types of strapping unit is that a tensioning wheel is driven by a manually actuated tensioning lever.

In order to apply a tension to the strap loop, the tensioning wheel has to be caused to rotate by means of the tensioning lever. By means of a frictional lock between the tensioning wheel and the strap layer in contact with it, the strap layer can be moved in the direction of a supply reel of the strap, as a result of which the strap loop becomes smaller and the strap tension consequently becomes greater. Conventionally, the tensioning lever can be moved only over a limited angular range, for example 120°, in one direction of rotation. However, the tensioning-wheel rotation associated therewith does not suffice in order to obtain a sufficient strap tension. For this reason, it is necessary to actuate the tensioning lever a number of times by moving the latter to and fro in an oscillating movement between two end positions of rotation. So that the tensioning wheel is not moved back again here counter to the tensioning direction of the strap, the tensioning lever is connected to the tensioning wheel via a coupling.

In the case of previously known strapping units of the type mentioned at the beginning, the coupling is designed here as a ratchet having a spring-loaded catch which engages radially in correspondingly shaped gaps of a wheel. Such a coupling of a tensioning drive is realized, for example, in the unit from the same applicant which is sold under the designation CM 14.

What may not be satisfactory, however, with this previously known solution is that, in particular, the catch has to be of relatively solid design on account of the high forces and torques which are in action, and this coupling therefore requires a large amount of space and involves a high weight.

SUMMARY OF THE INVENTION

The invention is therefore based on the object of proposing a coupling for an operative connection between the tensioning lever and the tensioning wheel, which coupling is designed more favorably in terms of the structure in comparison with catch-type couplings.

This object is achieved according to the invention in the case of a strapping unit of the type mentioned at the beginning by an axial coupling being provided in a force flux from the tensioning lever to the tensioning wheel. Within the context of the present invention, axial couplings—or else axial surface couplings—can be understood to be those couplings in which one coupling part has, as constituent part, an axial surface in the region of the tensioning shaft, i.e. a surface or a plane of the surface through which the tensioning axis runs, and this axial surface or plane can be brought into operative connection with another coupling part to be coupled on. In a structurally simple and preferred embodiment, the axial surface can be one end side of the tensioning shaft itself. However, the axial surface can also surround the tensioning shaft. A second axial surface assigned to the tensioning lever can then enter into and come out of operative connection with the first one, in order to complete or cancel a force flux between the tensioning lever and the tensioning wheel.

It has proven particularly preferable if a plurality of segments which can be brought into and out of engagement are present in each case on the two axial surfaces. Segments of this type can each have one flank surface which is brought to bear against a flank surface of a segment of the respectively other coupling part. The positive lock arising by this means then leads during a movement of the tensioning lever in a predetermined direction of rotation to a rotational movement of the tensioning wheel. The flank surfaces should preferably be aligned parallel and radially with respect to the tensioning axis. Since a plurality of flank surfaces are simultaneously in engagement with one another, it is possible to transmit a high torque in a small space. The size of the transmittable torque can be increased or reduced in a specific manner by increasing the sum of the total area of the flank surfaces.

In order for the tensioning lever to be decoupled from the tensioning shaft in a direction of rotation opposed to the direction of rotation assigned to the positive lock, it may be expedient to design the segments in such a manner that they can slide on one another. In order to achieve this, one structural solution may consist in providing the segments with surfaces which rise in a ramp-like manner with respect to the axial surface.

In a further preferred embodiment of the invention, the segments of both axial surfaces can be designed as a Hirth-type serration. The geometrically simple Hirth-type serration has all of the above-described advantages and can be manufactured comparatively simply.

Further preferred refinements of the invention emerge from the dependent claims, the description and the drawing.

BRIEF DESCRIPTION OF THE DRAWINGS

The invention will be explained in greater detail with reference to an exemplary embodiment illustrated schematically in which:

FIG. 1 shows a perspective illustration of a strapping unit according to the invention;

FIG. 2 shows the strapping unit of FIG. 1 in a different perspective illustration;

FIG. 3a shows a longitudinal sectional illustration of the strapping unit of FIG. 1, in which the sealing-device lever is situated in an open end position;

FIGS. 3b-3d show an illustration of the strapping unit according to FIG. 3a, in which the sealing-device lever is shown in two intermediate positions and in the sealing end position;

FIG. 4 shows an illustration of a cross section running both through a rotational axis and a tensioning axis of the strapping unit;

FIG. 5 shows a further perspective illustration of the strapping unit, in which, in comparison to the illustration of FIGS. 1 and 2, a housing and a tensioning lever is removed;

FIG. 6 shows a sectional illustration along a tensioning axis;

FIG. 7 shows a perspective illustration of a tensioning lever provided with a coupling part of an axial coupling;

FIG. 8a shows a detail of a longitudinal section through engaged segments of a Hirth-type serration;

FIG. 8b shows an illustration according to FIG. 8a after a relative movement of two coupling parts on which the segments are arranged;

FIG. 9 shows an illustration of the strapping unit according to FIG. 3a with a strap loop inserted into the strapping unit;

FIG. 10 shows a further exemplary embodiment in an illustration according to FIG. 3a;

FIGS. 11, 12 show two illustrations of the strapping unit from FIG. 10, in which the sealing-device lever is shown in an intermediate position and in the sealing end position;

FIG. 13 shows a sectional illustration of the exemplary embodiment from FIG. 10 according to the illustration from FIG. 4.

DETAILED DESCRIPTION OF THE INVENTION

The exclusively manually actuated strapping unit shown in FIGS. 1 and 2 has a base plate 1 and a die-plate carrier 3, which is mounted pivotably on a bearing point 2 in the region of a front end 1a of the base plate 1. The die-plate carrier is covered in FIGS. 1 and 2 by a housing 4, but can be seen better in FIGS. 3a-3d. A positionally fixed carrier 5, which is connected integrally with the base plate 1 and is used in particular for accommodating bearing points is arranged laterally next to the die-plate carrier. The carrier can be seen in particular in FIG. 5.

As can be gathered in particular from FIGS. 3a to 3d, in the base plate 1 a punch 6 is inserted from above into a recess of the base plate 1. The punch 6 is fastened to the base plate 1 by means of at least one screw 7, introduced from a supporting surface 1b of the base plate 1, and bolt pins 8 and is a constituent part of a sealing device. A bearing surface 1d of the base plate 1 is provided directly behind the punch, in the direction of the rear end of the base plate. Finally, in the region of the rear end 1c of the base plate 1 a toothed plate 9 (FIG. 9) which is profiled on an upper side is inserted into the base plate and the one retaining plate 10 bears against it. The retaining plate 10 is screwed onto the base plate 1 and therefore fixes the toothed plate 9 in place.

The die-plate carrier 3 is mounted at the front end of the carrier 5 of the strapping unit by means of a rotary bearing 12 designed as a radial rolling bearing. A rotational axis of the rotary bearing 12 runs essentially transversely to an alignment of the strap arranged in the strapping unit and therefore perpendicularly with respect to the plane of projection in FIGS. 3a-3d. As a further constituent part of the sealing device, the die-plate carrier 3 has a two-part die-plate 13, of which only the front die-plate part 13a can be seen in the illustration of FIG. 1. The die-plate 13 is inserted into a recess on the lower side 3a of the die-plate carrier, which side faces the base plate 1. In order to secure the die-plate 13, it is pushed onto a pin 17 of the die-plate carrier 3 and

is screwed to the die-plate carrier 3 by means of two screws 15, 16 (FIG. 3a). The die-plate 13 and the punch 6 can be designed in a manner substantially corresponding to the sealing tools shown in DE 38 41 489 C2 or CH 659 221 A5. Toward the rear end of the strapping unit a notching tool 18, which is designed as a notching blade, is inserted into the die-plate carrier, likewise on the lower side thereof. A notched cutter 18a of the separating means protrudes by a predetermined length over the lower side 3a. The notching tool 18 belongs to a separating means of the strapping unit, with which a section of a steel strap can be severed by a shearing operation.

On a side facing away from the base plate 1, the die-plate carrier 3 has, on an upper side, a receptacle 19 for a transmission element 20. For this purpose, the receptacle 19 is of approximately fork-shaped design, the two fork struts 19a, 19b in each case being bent toward each other. The fork strut 19b, which is closer to the rear end 1b of the base plate, is provided with an inner rolling surface 19c which is shaped in such a manner that the transmission element 20 can roll on it for a certain distance during a pivoting movement of the die-plate carrier 3. The shape of the other fork strut 19a is configured to the effect that the transmission element 20 can, on the one hand, move in the predetermined manner in the receptacle 19 during a pivoting movement, but, on the other hand, is retained securely between the two fork struts 19a, 19b.

In the exemplary embodiment illustrated, the transmission element 20 is a roller which, with its eccentric axis 23, is arranged eccentrically with respect to a rotational axis 24 of a rotational bearing 22, which is explained in more detail below (cf. also FIG. 4). The eccentricity is denoted in FIG. 3b by E. In order to reduce the wear, this roller is provided with an outer sliding ring with which the transmission element 20 comes into contact with the fork struts 19a, 19b of the die-plate carrier 3. As can be seen in particular from FIG. 2, the rotational bearing 22 is supported on the carrier 5 via a bearing fork 25. The rotational bearing can be actuated via a sealing-device lever 26 which is connected non-rotatably to a shaft 27 of the rotational bearing (for rotation in common). Also connected to the positionally fixed bearing fork 25, which is connected to the carrier 3, is an abutment 28 against which a rocker 30 (described in greater detail below) is supported via a spring 29.

As can be gathered in particular from the sectional illustration of FIG. 4, the sealing-device lever 26 is arranged non-rotatably with an annular part 26a on the rotational shaft 27 (for rotation in common). Annular ends 25a, 25b of the bearing fork 25 are also provided on both sides of the sealing-device lever. A respective needle bearing 33a, 33b is provided in the ends 25a, 25b of the bearing fork 25, for the mounting of the rotational shaft 27.

One of two fork-shaped limbs 30a, 30b of the rocker 30 is on one hand arranged between the sealing-device lever 26 and a first of the ends 25a of the bearing fork and on the other hand arranged on the right-hand, outer side on the rotational shaft 27 next to the second end 25b of the bearing fork. The rocker 30 can be seen, inter alia, also in FIG. 2 and will be explained in greater detail below. The limbs 30a, 30b of the rocker are also mounted on the rotational shaft 27 by means of needle bearings 34a, 34b. In the illustration of FIG. 4, the transmission element 20 arranged on the other end of the rotational shaft 27 can finally also be seen. The transmission element 20 is mounted rotatably with respect to the rotational shaft 27 by means of a sliding bearing 35.

As has already been discussed above, the rocker 30 of the tensioning device is mounted rotatably on the rotational

shaft 27, at an end of the said rotational shaft which lies opposite the transmission element 20. Since the rocker 30 is arranged on the same shaft as the sealing-device lever 26, the rotational axis 24, by means of which the sealing-device lever 26 causes the rotational shaft 27 to rotate, is aligned with a pivot axis 36 of the rocker 30. However, since the rocker 30 is arranged with radial bearings on the shaft, rotational movements of the shaft 27 are decoupled from the pivoting movement of the rocker 30. Both the rotational axis 24 and the pivot axis 36 run essentially parallel to the axis of the rotational bearing 12.

According to FIG. 5, a handle 37 is also connected fixedly to the rocker 30 and can be used to actuate the rocker in the form of a pivoting movement about the rotational axis and pivot axis 24, 36, respectively. The compression spring 29 which is supported on the abutment 28 acts on the handle 37. The rocker 30 can therefore be pivoted from a tensioning position, which is shown in the figures and in which a tensioning wheel 38 (FIG. 3a) bears against the toothed plate 9 or against a strap guided over the toothed plate, into a neutral end position (not shown in the figures) and back again into the tensioning position. In the neutral end position, the tensioning wheel is arranged at a distance from the toothed plate. Without acting on the rocker, the said toothed plate always assumes the tensioning position because of the spring force acting on it.

A tensioning lever 39, with which the tensioning wheel 38 (FIG. 3a) can be caused to rotate, is fitted on an end of the rocker 30 lying opposite the rotational bearing 22 (FIG. 2). As can be seen in particular from FIG. 1 and FIG. 4), a tensioning shaft 43 is mounted rotatably in a cylindrical part 40 of the rocker 30. At the two ends of the tensioning shaft 43, the tensioning lever 39 is situated at one end and the tensioning wheel 38, which is arranged non-rotatably on the tensioning shaft (for rotation in common), is situated at the other end. As can be seen in FIGS. 4 and 6, the tensioning shaft is mounted rotatably in the rocker 30 by means of a clamping-body free-wheel based on a radial needle bearing. For the present exemplary embodiment, the sleeve-type free-wheel with mounting HFL 1626, which is provided by INA Wälzlager Schaeffler oHG, Herzogenaurach (Germany), shown inter alia, in Catalog 306/1991 has proven suitable. Free-wheels of this type only permit rotation in one direction of rotation. They block the shaft supported by them against rotations in the other direction of rotation.

In the region of the tensioning lever 39, an axial coupling 44 (FIG. 4 and FIG. 6) is situated on the tensioning shaft—and therefore in the force flux between the tensioning lever and the tensioning wheel. The axial coupling 44 can be used to bring the tensioning lever 39, which can be rotated by means of a radial bearing (not illustrated in greater detail), together with the tensioning shaft 43 into and out of engagement.

The axial coupling 44 has two coupling parts 44a, 44b which are both provided with a Hirth-type serration 45 (FIG. 5 and FIG. 7). As is shown in particular in FIG. 6, one of the two coupling parts 44a, 44b has a bushing on the side of the lever, on which the lever is fastened, and, on the other side, a driver provided with a linear internal toothing. The driver 44b is arranged on a linear external toothing 46 of the tensioning shaft 43, which toothing is on the circumference, and is connected to the latter in a positive locking manner. The driver 44b is supported via a compression spring 47 against a bearing ring 48 which, in turn, bears against a shoulder 43a of the tensioning shaft 43. If a correspondingly large compressive force is exerted on the driver 44b in the

direction of a tensioning axis 49 running parallel to the rotational axis 24, then the driver 44b can be axially displaced counter to the spring force in the direction of the tensioning wheel 38 on the tensioning shaft 43 and can subsequently be pushed back again into its initial position by the tensioned spring.

As sketched in FIGS. 8a and 8b, the Hirth-type serration 45 has, on annular surfaces of each coupling part 44a, 44b which surfaces are orientated essentially orthogonally with respect to the tensioning axis, a plurality of segments 45a, 45b which are geometrically identical in each case, rise with a ramp-like surface 50 by the amount a in the direction of the tensioning axis 49 and then drop with a steep flank surface 51, which runs essentially parallel to the tensioning axis, to the foot of the respectively adjacent segment. The flank surfaces 51 are aligned at least substantially radially with respect to the tensioning axis 49. With regard to longitudinal sections which run parallel to the tensioning axis, the segments are therefore of essentially triangular design.

Owing to the described arrangement of the segments 45a, 45b of the two coupling parts 44a, 44b, the ramp-like surfaces 50 of segments 45a, 45b of different coupling parts slide on one another in a sheet-like manner only in a relative direction of rotation as is indicated in FIG. 8b. At the end of this sliding movement, the flank surface 51a of the segment 45a then always passes behind the flank surface 51b of a segment 45b of the other coupling part 44b. Since both the tensioning lever 39 and the tensioning shaft 43 do not change their position in the axial direction, it is necessary, in order to execute this movement, for the driver 44b to be pressed in the manner already described against the spring 47 and in the process to execute an axial displacement, the length of which corresponds to the height or length of the flank surfaces 51. During this movement the tensioning lever 39 can therefore be rotated about the tensioning shaft 43 which is stationary and is blocked by the free-wheel 41. The tensioning lever 39 is therefore decoupled from the tensioning shaft. If, in contrast, the tensioning lever 39 is actuated in the reverse direction of rotation, flank surfaces 51a of the tensioning lever press against flank surface 51b of the driver 44b. The tensioning lever is coupled to the tensioning shaft, as a result of which the rotational movement of the tensioning lever causes a rotation of the tensioning wheel 38.

In order to tension a strap loop around a packaged item 58 (merely shown schematically in FIG. 9) using the illustrated strapping unit according to the invention, first of all the strap can be placed loosely around the packaged item 58, so that two strap layers 60, 61 lie one above the other in the region 50 of the free strap end 59. The strapping unit is then arranged by means of its supporting surface 1b of the base plate 1 on the packaged item, the die-plate carrier 3 being arranged in its open end position and the tensioning wheel 38 being arranged in its neutral end position. As a result, the two strap layers 60, 61 lying one above the other can be guided over the base plate 1 of the strapping unit, with the result that the strap is situated between the die-plate 13 and the punch 6. By means of a pivoting movement of the rocker 30 counter to the spring force of the compression spring 29 a gap can then also be provided between the tensioning wheel 38 and the toothed plate 9. For this purpose, an operator can grip the handle 37 and the sealing-device lever 26 which is arranged in its open end position, with one hand and can press the handle 37 upward in the direction of the sealing-device lever 26.

After the two strap layers 60, 61 have been introduced into the gap, the handle is released, as a result of which the

compression spring 29 moves the rocker 30 back again in the direction of the toothed plate 9 into its tensioning position. The two strap layers 60, 61 are thereby clamped between the tensioning wheel 38 and the toothed plate 9. In this connection, the lower strap layer 60 rests with the free strap end 59 on the punch 6 and on the bearing surface 1d of the base plate. The other strap layer 61 which leads to a supply reel (not illustrated) is situated above the free strap end and projects behind the tensioning wheel out of the strapping unit. This situation is shown in FIG. 9.

The strap loop can then be tensioned by actuation of the tensioning lever 39. For this purpose, the tensioning lever 39 is pivoted to and fro a number of times between its two end positions. During its pivoting movement in the anticlockwise direction (with regard to the illustrations of FIGS. 3a-3d) there is a positive lock between the two coupling parts 44a, 44b. The tensioning wheel is therefore caused to rotate in the anticlockwise direction. Because of a frictional lock between the upper strap layer 61 and the tensioning wheel 38, the upper strap layer is pulled further out of the strapping unit and the strap loop is provided with tension. In contrast, the lower strap layer 60 is retained unchanged in position because of the profiling of the toothed plate 9. During the pivoting movement of the tensioning lever in the clockwise direction, in contrast, the positive lock between the coupling parts 44a, 44b, and therefore also between the tensioning lever 39 and the tensioning shaft 43, is canceled. The tensioning wheel 38 is therefore not carried along in this direction of movement. Owing to the free-wheel 41, the tensioning wheel 38 and the tensioning shaft 43 also do not rotate back during the decoupling of the tensioning lever 39, but remain in their current rotational position. The oscillating movement of the tensioning lever is repeated until a sufficient tension is applied to the strap.

The strap loop is subsequently sealed. For this purpose, the sealing-device lever 26 and the transmission element 20 are transferred from its open end position (FIG. 3a) into its sealing end position (FIG. 3d). In the exemplary embodiment illustrated, during this process the sealing-device lever covers an angle of rotation α of approximately 140°. In the process, the eccentrically mounted roller rolls along the surface 19c of the limb 19b of the receptacle 19. The eccentricity E of the roller rotates here in the same direction of rotation as the sealing-device lever. At the end of the rotational movement, the roller bears against the surface 19c in the region of the free end of the limb 19b. The limb 19b is aligned to the angular position of the eccentricity in such a manner that, if possible, already after the first contact of the die-plate with the upper strap layer, the lever arm of the torque exerted on the die-plate carrier, the said lever arm being referred to in the drawings by H, is as large as possible. The lever arm arises as the distance of the rotary bearing 12 from the direction of the force normal K with which the roller presses at a particular moment in each case against the limb 19b. In the exemplary embodiment illustrated, the size of the lever arm H even increases slightly toward the end of the pivoting movement of the die-plate carrier rotating in the clockwise direction, with respect to the direction of looking at FIGS. 3a to 3d.

In FIGS. 3a to 3d, which show the two end positions and an intermediate position of the sealing-device lever 26 and of the transmission element 20, it is also illustrated that the force normal encloses a negative angle β with respect to a normal N of the supporting surface 1b, which normal runs through the rotational axis 24, or of the bearing surface 1d which is parallel thereto. Starting from the open end position, this negative angle becomes increasingly large up

to the sealing end position. In this connection a "negative angle" is understood to be an angle which—starting from the normal N—is to be measured in the anticlockwise direction. In FIGS. 3a-3d, it can also be seen particularly readily that the normal N of the supporting surface which normal runs through the rotational axis 24, lies in the tensioning direction (arrow 62) behind the point at which the notching tool 18 presses against the base plate 1 or against the strap 61.

Owing to the comparatively long lever arm H, the strap can be deformed right from the beginning of contact of the upper strap layer with that end of the die-plate 13 which is at the front in the tensioning direction 62. Since the lever arm H can even increase slightly toward the end of the pivoting movement due to its construction, the torque increases whenever the sealing device also has to act on a relatively larger strap surface. By this means, it is reliably ensured that an additive-free, i.e. in particular a lead-free and weld-free, seal is formed by the die-plate and the punch in the strap itself, the said seal not being released even at high strap tension. Directly before the sealing end position is reached, the notched cutter notches into the upper strap layer, which is still connected to a strap supply and severs it from the strap supply. Subsequently, the sealing-device lever can be transferred again into its open end position, the tensioning wheel can be lifted off the strap by actuation of the rocker and the strapping unit can be removed by guiding it away laterally from the finished strap loop.

FIGS. 10-13 show a further exemplary embodiment of a strapping unit according to the invention. Since the latter has great similarity with the previously described exemplary embodiment, only the differences will be discussed below.

FIG. 10 shows that, in contrast to the first exemplary embodiment, here a roller 105 is inserted in a half shell 104, which is placed in the die-plate carrier 103, below the rotational axis 124. The half shell 104 has approximately the shape of a hollow cylinder severed along a longitudinal axis, the longitudinal axis of the half shell 104 running approximately parallel to the rotational axis 124. Furthermore, a retaining strip 108 is screwed on the die-plate carrier 103, directly in front of the half shell 104. The said retaining strip has a surface 108a which is in the shape of a circular arc in cross section, adjoins the half shell 104 and therefore also surrounds part of the cylindrical circumferential surface 105a of the roller 105. The roller 105 is therefore arranged in a freely rotatable manner in the half shell 104, which is provided with a sliding lining 104a, the roller 105 being prevented from falling out of the half shell 104 by the retaining strip 108.

A section of the rotational shaft 127 situated directly above the roller 105 is designed as a cam 109 which is arranged eccentrically with respect to the rotational axis 124. In the case of this exemplary embodiment, the cam 109, which is connected integrally to the rotational shaft, therefore takes over the function of a transmission element 120. By means of an eccentric surface 109a of the cam, the rotational shaft 127 is in contact with the circumferential surface 105a of the roller 105 and therefore transmits a rotational movement of the rotational shaft 127 to the die-plate carrier 103. By means of the differing distance of the eccentric surface 109a along the circumference of the eccentric cam 109 with respect to the rotational axis 124 and the rotational movement of the rotational shaft 127, during a pivoting movement (in the anticlockwise direction with regard to the illustration of FIG. 10) of the sealing-device lever 126 the die-plate carrier 103 can be pressed by the cam 109 from its open end position into its sealing end position. In the sectional illustration of FIG. 13 (which corresponds to

the illustration of FIG. 4) of the second exemplary embodiment, the structure of the unit, which is slightly changed with respect to the first exemplary embodiment, in the region of the transmission element 120 can likewise be seen. This illustration also reveals the cam 109 which is connected integrally to the rotational shaft and acts on the roller 105 mounted in the die-plate carrier. 5

If the sealing-device lever 126 is moved back out of its sealing end position in the reverse direction of pivoting, then in this case a hook 110, which is shown in FIGS. 11 and 12, 10 grips, in a positively locking manner, under a projection (which cannot be seen in the figures) of the die-plate carrier 103 and carries along the die-plate carrier 103. In the illustrations of FIGS. 12 and 13, the projection is situated behind the half shell 104. During the further course of the 15 rotational movement of the rotational shaft 127, the die-plate carrier is then, on account of its rotational movement, which is caused by this means, about the bearing 112, lifted off the base plate 101 and transferred by the hook 110 into its open end position. In the strapping operation which follows next, 20 on account of its rotational movement which then takes place in the anticlockwise direction (with respect to FIGS. 10-13, the hook 110 releases the die-plate carrier again, with the result that the latter can be transferred by the cam into its sealing end position.

Finally, it is revealed in FIG. 11, which shows the die-plate carrier 103 shortly before it reaches its sealing end position, that at this time the contact region between the cam 109 and the roller 105 is situated approximately directly above the notching tool 118. In the sealing end position itself, which is shown in FIG. 12, the contact region then migrates behind the notching tool 118. In another exemplary embodiment (not illustrated), however, the contact region could also be arranged approximately above the notching tool, in the sealing end position. Also in conjunction with these exemplary embodiments, the abovementioned positional details of the contact region are related in each case to the course of the tightening straps through the strapping unit, specifically to the direction from the bearing 112 to the rear end of the strapping unit (arrow 162). 25

In a similar manner as in the first exemplary embodiment, a direction of a force transmitted onto the die-plate carrier by the transmission element 120 should preferably also be orientated at least approximately vertically onto the strap. Furthermore, a force normal, which runs through the rotational axis 124 in the sealing end position and through the contact point between the cam 109 and the roller and which arises from the transmitted force, can preferably run approximately through the separating means or, with respect to the direction 162, can intersect the base plate of the unit 30 behind the separating means.

What is claimed is:

1. A manually actuated strapping unit for wrapping a 35 tightening strap around a packaged item, said unit comprising:

a base plate which is provided with a supporting surface adapted to be placed on the packaged item;

a sealing device for permanently connecting two layers of the tightening strap to each other;

a tensioning device for applying a tension to the tightening strap, said tensioning device having a tensioning shaft, a tensioning wheel arranged on said tensioning shaft and a manually actuated tensioning lever for actuating said tensioning wheel;

separating means for severing the tightening strap; and 60 an axial coupling selectively coupling said tensioning lever with said tensioning wheel, said axial coupling

comprising two coupling parts which have a plurality of engaging segments that can be brought into and out of engagement;

wherein said segments are geometrically identical and said coupling parts have the same number of said identical segments.

2. A manually actuated strapping unit for wrapping a tightening strap around a packaged item, said unit comprising:

a base plate which is provided with a supporting surface adapted to be placed on the packaged item;

a sealing device for permanently connecting two layers of the tightening strap to each other;

a tensioning device for applying a tension to the tightening strap, said tensioning device having a tensioning shaft, a tensioning wheel arranged on said tensioning shaft and a manually actuated tensioning lever for actuating said tensioning wheel;

separating device for cutting the tightening strap; and

a Hirth coupling selectively coupling said tensioning lever with said tensioning wheel when said tensioning lever is operated in a first direction and decoupling said tensioning lever from said tensioning wheel when said tensioning lever is operated in a second, opposite direction.

3. The strapping unit according to claim 2, wherein said Hirth coupling comprises first and second coupling parts having two matching Hirth serrations, respectively, the first coupling part being coupled to and driven by said tensioning lever, the second coupling part being coupled to said tensioning wheel for driving said tensioning wheel when said matching Hirth serrations of said coupling parts are brought into engagement.

4. The strapping unit according to claim 3, further comprising a spring biasing said matching Hirth serrations of said coupling parts into engagement.

5. The strapping unit according to claim 4, wherein said spring is a coil spring through which an axis of said tensioning shaft extends.

6. The strapping unit according to claim 3, wherein each of said Hirth serrations comprises a plurality of alternately arranged ramp and flank surfaces, said flank surfaces being approximately parallel to an axis of said tensioning shaft.

7. The strapping unit according to claim 3, wherein each of said Hirth serrations comprises a plurality of alternately arranged ramp and flank surfaces, said flank surfaces extending radially with respect to an axis of said tensioning shaft.

8. A manually actuated strapping unit for wrapping a 50 tightening strap around a packaged item, said unit comprising:

a sealing device for permanently connecting two layers of the tightening strap to each other;

a tensioning device for applying a tension to the tightening strap, said tensioning device having a tensioning shaft, a tensioning wheel arranged on said tensioning shaft and a manually actuated tensioning lever for actuating said tensioning wheel; and

a coupling selectively coupling said tensioning lever with said tensioning wheel when said tensioning lever is operated in a first direction and decoupling said tensioning lever from said tensioning wheel when said tensioning lever is operated in a second, opposite direction;

wherein a sealing operation of said sealing device is independent of movements of said tensioning lever in both said first and second directions;

11

wherein said coupling comprises first and second coupling parts arranged on said tensioning shaft;

the first coupling part being coupled to and driven by said tensioning lever, the second coupling part being coupled to said tensioning wheel for driving said tensioning wheel when said coupling parts are brought into engagement;

said first and second coupling parts respectively having first and second surfaces facing each other in an axial direction of said tensioning shaft, said first and second surfaces having a plurality of segments that are engaged when said tensioning lever is operated in the first direction and disengaged when said tensioning lever is operated in the second direction; and

wherein said first and second surfaces are identical.

9. A manually actuated strapping unit for wrapping a tightening strap around a packaged item, said unit comprising:

a sealing device for permanently connecting two layers of the tightening strap to each other;

a tensioning device for applying a tension to the tightening strap, said tensioning device having a tensioning shaft, a tensioning wheel arranged on said tensioning shaft and a manually actuated tensioning lever for actuating said tensioning wheel; and

a coupling selectively coupling said tensioning lever with said tensioning wheel when said tensioning lever is operated in a first direction and decoupling said tensioning lever from said tensioning wheel when said tensioning lever is operated in a second, opposite direction;

wherein a sealing operation of said sealing device is independent of movements of said tensioning lever in both said first and second directions;

wherein said coupling comprises first and second coupling parts arranged on said tensioning shaft;

the first coupling part being coupled to and driven by said tensioning lever, the second coupling part being coupled to said tensioning wheel for driving said tensioning wheel when said coupling parts are brought into engagement;

said first and second coupling parts respectively having first and second surfaces facing each other in an axial direction of said tensioning shaft, said first and second surfaces having a plurality of segments that are engaged when said tensioning lever is operated in the first direction and disengaged when said tensioning lever is operated in the second direction; and

12

wherein said first and second surfaces define matching Hirth serrations.

10. The strapping unit according to claim 9, further comprising a spring biasing said matching Hirth serrations of said coupling parts into engagement, wherein said spring is a coil spring through which an axis of said tensioning shaft extends.

11. The strapping unit according to claim 9, wherein each of said Hirth serrations comprises a plurality of alternately arranged ramp and flank surfaces, said flank surfaces extending radially with respect to an axis of said tensioning shaft.

12. The strapping unit according to claim 9, further comprising a sealing device lever, different from said tensioning lever, for actuating said sealing device.

13. The strapping unit according to claim 12, further comprising a cutting device for cutting the strap, said cutting device being actuated together with said sealing device by said sealing device lever.

14. The strapping unit according to claim 12, further comprising

a base plate having a supporting surface adapted to be placed on the packaged item; and

a handle, different from said tensioning lever and said sealing device lever, for lowering said tensioning wheel on said base plate prior to tensioning the strap.

15. The strapping unit according to claim 12, wherein said tensioning wheel remains a rotational position thereof regardless of movements of said sealing device lever.

16. A manually actuated strapping unit for wrapping a tightening strap around a packaged item, said unit comprising:

a sealing device for permanently connecting two layers of the tightening strap to each other;

a tensioning device for applying a tension to the tightening strap, said tensioning device having a tensioning shaft, a tensioning wheel arranged on said tensioning shaft and a manually actuated tensioning lever for actuating said tensioning wheel; and

a coupling selectively coupling said tensioning lever with said tensioning wheel when said tensioning lever is operated in a first direction and decoupling said tensioning lever from said tensioning wheel when said tensioning lever is operated in a second, opposite direction; wherein

a sealing operation of said sealing device is independent of movements of said tensioning lever in both said first and second directions; and

said coupling is a Hirth coupling.
